UNITED STATES PATENT OFFICE

2,366,556

HIGH-FREQUENCY APPARATUS

John P. Blewett, Scotia, N. Y., assignor to General Electric Company, a corporation of New York

Original application March 1, 1940, Serial No. 321,746. Divided and this application March 27, 1941, Serial No. 385,437

4 Claims. (Cl. 179—171)

The invention described herein was previously described in application Serial No. 321,746, filed March 1, 1940, as a joint application of Simon Ramo and John P. Blewett.

The invention relates to improvements in electronic apparatus for obtaining amplification and other conversion effects at frequencies so high that electron transit time considerations play a controlling part in the operation of the apparatus.

In certain respects the invention represents an application of the so-called "velocity modulation principles," which are described in U. S. Patent 2,220,839, granted November 5, 1940, in the name of W. C. Hahn. However, whereas Hahn has employed an elongated beam tube of the cathode ray type for producing the effects desired, the present invention utilizes a structure in which the electron beam is caused to traverse a more or less helical path, thus realizing a greater degree of compactness as well as various operational advantages which will be explained in the following.

The generic aspects of helical path devices of the type in question are claimed in the aforesaid prior application Serial No. 321,746, and the present case relates specifically to a particular and especially advantageous arrangement by which the invention disclosed in the prior application may be carried out. Briefly stated, this arrangement comprises the combination of an elongated linear cathode, means for producing orbital motion of electrons emitted by the cathode and for causing the orbitally moving electrons to progress axially along the cathode, and means acting on the axially progressing electron stream at mutually spaced regions to produce useful high frequency effects.

The invention may best be understood by reference to the following description taken in connection with the drawings, in which Fig. 1 represents a diagrammatic perspective view of an apparatus suitably embodying the invention; Figs. 2 and 3 are partial sectional views respectively taken on lines 2—2 and 3—3 of Fig. 1, and Figs. 4 to 6 are diagrammatic representations useful in explaining the invention.

Referring particularly to Fig. 1 there is shown an evacuated envelope 10 which encloses an elongated linear cathode, consisting, for example, of an activated metal filament. In the arrangement shown, the emissive portion of the cathode is limited to the region between the points *e* and *f*, although this is by no means an essential condition. Surrounding the cathode and extending

generally coaxially with it there is provided a high frequency electrode system including a series of mutually separated cylindrical parts 12 to 16, the function of which is described in detail in the following.

The cylinder 12, which subtends a major portion of the cathode 11, is maintained at positive potential with respect to the cathode so as to produce radial motion of the electrons emitted from it. This motion is converted into orbital motion by means of a strong magnetic field established in a direction parallel to the cathode, for example, by means of a coil 19. Also a unidirectional potential is impressed between the electrode 12 and the electrode 13 for producing an axial field adapted to cause the electrons to move axially along the electrode system in the direction of the higher numbered electrodes. If desired, further unidirectional potentials may be applied to the other electrodes of the system (i. e. the electrodes 14, 15 and 16) to increase this axial motion, but satisfactory operation of the apparatus will be obtained if all these parts are at a common potential with the electrode 13. A direct current source such as a battery 20 may be employed to maintain the potential relationships referred to.

As appears more clearly in Fig. 2, the electrode 13 consists of a split cylinder having two semi-cylindrical conducting parts 13a and 13b, which are insulatingly spaced and which define a generally cylindrical chamber between them. In the use of the apparatus these parts are subjected to an alternating difference of potential by means of an appropriate input circuit which is illustrated diagrammatically as including a pair of parallel conductors 21 and 22. These conductors are assumed to constitute a standing wave transmission line (e. g. a quarter wave line) which may be excited in any desired fashion from a high frequency signal source. A common battery connection 23 for the two conductors is provided for maintaining the average potential of the electrode parts 13a and 13b at a desired value.

Before explaining the operation of the apparatus as so far described, it will be helpful to refer to the matters represented in Figs. 4 to 6. In Fig. 4, the solid line *B* may be taken to represent the path of an electron whose velocity corresponds to the average or unmodulated velocity of an electron stream of which it forms a part. The point *o* is considered to represent a region in which the stream is subjected to a high frequency modulating potential. An electron which passes the modulating agency in such time phase

as to be accelerated thereby may be expected to follow a path of somewhat greater radius than the path B, such enlarged path being represented, for example, by the dot-dash line C. On the other hand, decelerated electrons will describe a smaller orbit as indicated by the dotted line D. Theoretical analysis shows, however, that each electron will require precisely the same time to traverse its orbit and return to the point 0. Moreover, it is found that each electron will pass through the point 0 along a line substantially coincident with that of its initial transit.

Fig. 5 shows the way in which the considerations discussed above are affected by the presence of a component of axial velocity in the electron stream motion. Thus, in this figure, the solid line E represents the projected path of a helically moving electron of average velocity, while the dotted lines F and G respectively show (in side projection) the lines followed by electrons which are respectively accelerated and decelerated by the effect of modulating potentials applied as the various electrons traverse the region occupied by the line 0'. It will be noted that for the case of repetitive acceleration the electron orbit increases progressively, while for the case of repetitive deceleration a progressive decrease in electron orbit occurs. However, the trajectory of each electron causes it to pass repeatedly through the line 0'.

In order to understand the possibility of obtaining amplification effects as a result of the phenomena discussed in the foregoing, it will be helpful to refer to the action of a circularly moving electron stream which is caused to traverse a modulating gap subjected to cyclically varying potential gradients. This situation is illustrated diagrammatically in Fig. 6, which may be taken to show the conditions occurring at various points around the orbit of an electron stream which is caused to traverse a modulating gap at 0''. For the case illustrated, it is assumed that the frequency of potential variation across the gap is such that eight complete cycles of variation occur during the time required for a single electron to traverse its orbit. The solid dots *a* may be taken to represent individual electrons, and considered in the aggregate, they show the condition of the beam at a particular instant of time.

As the various electrons move azimuthally, those whose velocity exceeds the average beam velocity seek an orbit of greater radius, while the decelerated electrons seek an orbit of reduced radius. As a consequence of this action, observations taken between various closely spaced azimuthal planes will show that the electron density measured at most points around the electron path varies materially with time. This variation is mainly a function of the relative displacement of the centers of gyration of the various electrons and is found to be greatest between planes which are located approximately ninety mechanical degrees from 0'', such planes being indicated at *b* and *b'*.

It will be noted that at the instant which is represented in Fig. 6, considerable bunching of the electrons exists between the planes referred to at the upper side of the electron orbit, while a relative paucity of electrons is to be noted between the same planes at the other side of the orbit. On the other hand, this situation would be found to be reversed at an instant taken a half-cycle later. It is, therefore, apparent that on either side of the electron orbit the portion

of the beam between the planes *b* and *b'* will be characterized by a high degree of "charge density modulation," that is, cyclical variation of electron density with time. On the other hand, in a region displaced ninety degrees from that just considered, that is to say, between the planes *c* and *c'*, substantially no variations of the charge density with time will be observed, and it may therefore be said that at this point the charge density modulation of the beam is negligible.

The condition of negligible charge density modulation last referred to will be realized again when the beam returns to its starting point at the region 0'', and at this point the beam will be characterized by its initial, relatively uniform charge density, although the velocity variations produced by the primary modulating action of the modulating system will still exist in the beam. Upon a further traversal of the gap by the electron stream, these variations will be increased in accordance with the principles previously explained. Therefore, since the charge density modulation occurring between planes *b* and *b'* is a function of the velocity variation which produces it, it is apparent that such charge density modulation will be greater for each successive orbital passage of the electron stream. If desired, this effect may be still further increased by providing additional modulating means arranged to operate in the beam as it passes the region *c*—*c'*. Such modulating means should, of course, be correlated to the means acting at the point 0 in order to assure that the results obtained shall be of cumulative character.

As a result of the considerations stated in the foregoing, even a relatively slight velocity modulation produced at the modulating gap 0'' may, by additive action, be made to cause relatively great charge density variations in the region *b*—*b'*. Therefore, if some means are provided by which the charge density variations existing at *b*—*b'* can be utilized in an appropriate manner, the system as a whole may be employed for amplification purposes.

While the foregoing does not represent a complete statement of the theory applicable to the structure of Fig. 1 (a more exact treatment is given in an article by John P. Blewett and Simon Ramo at pages 635-641 of the Physical Review for April 1, 1940), it provides an approximate viewpoint useful in visualizing the operation of the structure. It may be observed in the first place that the input circuit 21—22 functions to produce cyclically variable voltages across the gaps which separate the electrode parts 13a and 13b. In accordance with the discussion given above, therefore, it may be assumed that if the circumferential dimensions of the parts are properly correlated to the orbital velocity of the electrons and to the operating frequency of the system, cumulative modulation effects may be obtained as the various electrons successively and repetitively traverse the said interelectrode gaps. Moreover, the velocity variations thus produced may be expected to result in even greater charge density variations in the more advanced portions of the electron stream.

Useful output voltages are obtained with the apparatus described above by making the electrode 15 also of a split cylinder construction, as shown in Fig. 3 and by connecting the parts 15a and 15b to an appropriate output circuit which is represented diagrammatically as including a pair of parallel conductors 24 and 25. As the

various components of the previously modulated beam successively traverse the gaps existing between the electrode parts 15a and 15b, excitation of these parts will be produced, and an output voltage of significant magnitude (i. e. greater than the magnitude of the input voltage) will be developed across the terminals of the output circuit. After its passage through the electrode 15 the electron stream may be collected by means of an appropriately positioned anode 26.

It is desirable with the construction above described to prevent radially moving electrons from reaching the surface of the envelope 10 and thus producing objectionable wall-charging. To this end the electrodes 12, 14 and 16 are provided with flanged extensions 27 which overlap the interelectrode gaps and prevent egress of electrons. Functionally similar flanges 28 are provided in connection with the longitudinally extending gaps which exist between the respective parts of the electrodes 13 and 15.

It will be noted that in the construction of Fig. 1, the input and output gaps are in a common plane rather than being 90 degrees displaced as might be expected from the discussion given in connection with Figs. 4 and 5. The possibility of this arrangement, which has been found satisfactory for a particular condition of operation, is explained in part by the relatively great effect of space charge in a system in which the electron source comprises a central filament as above described. In this situation, the theoretical considerations which indicate a quadrangular displacement of the input and output gaps for cases of relatively low electron density no longer apply with complete accuracy, but a determination of the best relationship between the location of the input gaps and the location of the output gaps may readily be made by experimental methods.

It should also be pointed out in connection with the apparatus of Fig. 1 that the arrangement shown does not necessarily permit all the emitted electrons to follow orbits of uniform radius. It appears, however, that the net effect is to establish a rotating and axially progressing space charge which produces high frequency effects generally indistinguishable from those caused by an electron stream whose form and course are more definitely fixed.

In the foregoing the invention has been described by reference to particular embodiments. It will be understood, however, that numerous modifications may be made by those skilled in the art without departing from the invention. I, therefore, aim in the appended claims to cover all such equivalent variations as come within the true spirit and scope of the foregoing disclosure.

What I claim as new and desire to secure by Letters Patent of the United States is:

1. In high frequency apparatus, the combination which includes a generally linear cathode, means for producing radial motion of electrons emitted from said cathode and for converting such radial motion into orbital motion about the cathode, means positioned at a first region along the axis of the cathode for producing cyclically variable potential gradients which act at least partially tangentially to the orbital path of the electrons thereby to develop variations in the orbital velocities of the electrons as they traverse such region, means for producing axial progression of the orbitally moving electrons along the cathode, and energy-abtracting means including an output circuit arranged to be affected by the

variations existing in the electron stream at a region which is displaced from the said first region in a direction along the axis of progression of the stream.

- 5 2. In high frequency apparatus, the combination which includes a generally linear cathode, means for producing radial motion of electrons emitted from said cathode and for converting such radial motion into orbital motion about the cathode, spaced conducting parts defining a relatively elongated gap which extends parallel to the cathode in proximity to the outer boundary of the orbitally moving electron stream, means for applying a high frequency voltage between the said conductive parts to vary the orbital velocity of the electrons in accordance with the variations of the potential gradients thus established across the said gap, means for producing axial progression of the orbitally moving electrons along the 10 cathode, another pair of spaced conducting parts defining a second gap which extends generally parallel to the first gap and in a region which is displaced therefrom in a direction along the axis of progression of the stream and circuit means 15 connected between the second named pair of conducting parts for excitation thereby in accordance with the variations which exist in the electron stream upon its traversal of the said second gap.
- 20 3. In high frequency apparatus, the combination which includes an elongated cathode, an electrode system including at least two aligned tubular electrode structures coaxial with the cathode, said two structures being each axially divided into two mutually spaced parts having gaps between them, a field-producing system for causing radial motion of electrons emitted from the cathode and for converting said radial motion into axially progressive orbital motion along a path 25 having the cathode as its central axis, an input circuit for applying a high frequency voltage between the parts of one of the said divided structures, thereby to develop variations in the orbital velocities of the electrons as they traverse the 30 gaps between such parts, and an output circuit connected between the parts of the other subdivided structure and responsive to variations existing in the electron stream as it traverses the gaps between such parts.
- 35 4. In high frequency apparatus, the combination which includes an elongated filamentary cathode, a series of aligned conductive tubular structures coaxially surrounding the cathode, at least two of the structures being divided into 40 spaced semicylindrical parts defining axially extending gaps between their opposed edges, means for applying an electric field between the cathode and at least certain ones of the said structures to produce radial motion of electrons emitted by the cathode, means producing a magnetic field extending axially of the cathode to convert the radial motion of the emitted electrons into orbital motion, means for producing a field adapted to cause axial progression of the orbitally 45 moving electrons, means for applying a high frequency voltage between the semicylindrical parts comprising one of the said divided structures, thereby to develop variations in the orbital velocities of the electrons as they traverse the gaps between such parts, and an output circuit connected between the parts of the other divided structure and responsive to variations existing in the electron stream as it traverses such parts.

JOHN P. BLEWETT.
